HIGH-PRESSURE METAL VAPOR ELECTRIC
DISCHARGE LAMP

Henry Grainger Jenkins, Pinner, John Walter Ryde, London, and George Hulbert Wilson, Wembley Park, Middlesex, England, assignors to General Electric Company, a corporation of New York

Application November 10, 1937, Serial No. 173,782
In Great Britain November 11, 1936

1 Claim. (Cl. 176—122)

This invention relates to electric discharge lamps of the type comprising an envelope through which a high-pressure metal-vapor (HPMV) discharge is adapted to pass and material (hereinafter called luminescent material) outside that envelope adapted to be excited to luminescence by radiation from that discharge. The function of the luminescent material is usually to correct the colour of the discharge, that is to say, to supply visible radiation of wavelengths in which the radiation of the discharge is deficient; thus the lamp may be of the kind described and claimed in British patent specification No. 401,846. On the other hand the function of the luminescent material may be to increase the total luminous output without regard to colour. In either case the envelope must, of course, transmit radiation capable of exciting the luminescent material. But this does not mean that the envelope must be of quartz, at any rate if the purpose of the luminescent material is colour correction. For, as indicated in the said specification, zinc-cadmium sulphide activated by copper, which is excited by radiation to which glass is transparent, is a suitable material for supplying red light to supplement the deficiency of the mercury spectrum in that colour.

The most convenient place for the luminescent material is on the inside of the outer jacket. But the temperature of this jacket, though below that of the inner envelope, is often much above normal atmospheric temperature. Figure 1 of the accompanying drawings shows the temperature distribution over the outer jacket of a 400 watt high intensity mercury vapor lamp of a well-known commercial type, much used for street-lighting and like purposes. Here line 1 is a half-section of the inner envelope, 30 mm. in diameter, containing the electrodes 4 and 5, 160 mm. apart, line 2 is a half-section of the outer jacket, 50 mm. in diameter. Line 3 referred to axes X, T, gives the temperature T at points on the outer jacket distant X from one end of the outer jacket. It will be seen that the temperature is considerably more than 300° C. over a considerable central portion.

Now few luminescent materials operate satisfactorily at such a temperature. Their efficiency usually decreases notably even at a temperature as low as 180° C. The decrease is partly reversible and is restored when the temperature is reduced, but it is also partly permanent if the high temperature, combined with strong illumination, is maintained for many hours. The

reversible change is mainly or entirely determined by the nature of the material itself; the permanent change depends largely on the gases to which the material is subjected. But it is unnecessary to distinguish between permanent and reversible changes, since the temperatures at which they have to be taken into account are not very widely different; for either of them, in circumstances with which this invention is concerned, the critical temperature that must not be exceeded (which of course depends on the efficiency and on the permanence required) usually, if not always, lies between 140° C. and 300° C.

One method of avoiding loss of efficiency due to high temperature is to put the luminescent material, not in the lamp itself, but on some part of a fitting associated with the lamp, but sufficiently far from it to be at substantially atmospheric temperature. But then it is not always easy to secure that the primary light from the discharge and the secondary light from the luminescent material are adequately mixed, as is often required. It would be more convenient if the material could still be placed on the outer jacket, which must then be so large that it is below the critical temperature.

If the energy dissipated in the lamp is sufficiently small, for example 125 watts or less, and more particularly if the length of the discharge column is small, for example less than 20 mm. (these conditions are fulfilled in known lamps operating at vapor pressures much exceeding one atmosphere), the size of a spherical, or possibly cylindrical, outer jacket whose temperature is nowhere above 140° C. is not seriously inconvenient. But when the length of the discharge exceeds 100 mm. and the watts dissipated exceed 250, the size of a spherical or cylindrical jacket fulfilling this condition becomes inconvenient. The object of this invention is to avoid this inconvenience and to provide jackets fulfilling this condition that are not inconveniently large.

When the maximum temperature T_m of the jacket is given, the smallest possible jacket, if it were possible, would probably be an isothermal jacket, having the temperature T_m all over its surface. But it is not possible. If the envelope were suspended in free air, there would, of course, be isothermal surfaces around it, one of these would have any given temperature T_m . But there would be convection currents in the air, and the introduction of a solid jacket on which luminescent material could be placed

would distort these currents; it appears improbable that any jacket cooled by convection could have a uniform temperature all over its surface.

In these circumstances, the smallest jacket will probably be the most nearly isothermal, that is to say, that which for a given T_m has the highest mean temperature. It is probable further that there is only one such surface (other 10 conditions being constant, such as the material and the thickness of the jacket and the medium between it and the discharge envelope) or at most only a few such surfaces. The question therefore arises whether such a substantially 15 isothermal jacket will be practicable on other grounds, for example whether it will be sufficiently small and of a shape that can easily be made and coated with luminescent materials and that will lead to an adequate mixing of the primary and secondary light. The question can be 20 answered only by experiment.

The discovery on which this invention is based is that the answer is affirmative. When the lamp is operated with the discharge column vertical, a 25 jacket of a simple pear-shape, with the narrow end downwards approximates closely to the most nearly isothermal surface, is not unduly bulky, and is otherwise suitable.

In applying this discovery, it must be remembered that, if the discharge column is vertical and the space between the inner envelope and outer jacket is filled with gas at a pressure so low that convection in it transfers little heat to the jacket, the coolest parts of the jacket will always be at 30 the upper and lower ends, towards which little radiation is emitted. In order to bring these ends up to nearly the maximum temperature in the central portion of the jacket, the ends would probably have to be re-entrant. This would be 35 a disadvantage, not an advantage; accordingly in estimating whether a shape approximates closely to the most nearly isothermal surface, for the purpose of the invention, the ends through which not more than 10% of the total radiation issues may be neglected; a shape is not to be regarded as not approximately substantially isothermal, merely because, by a re-shaping of these ends, it could be made more nearly isothermal. The true criterion of approach to the most nearly isothermal surface is the uniformity of temperature over that part of the surface through which the greater part of the radiation issues.

To determine how far any given shape approximates to the most nearly isothermal, considerable experimenting is required. Accordingly we propose to define our invention, not in terms of the most nearly isothermal surface, but in terms of the temperature distribution over the jackets that our experiments have shown to approach as nearly as possible (subject to the foregoing consideration) to that surface. These experiments show that it is possible to obtain jackets in which, over the whole of a surface on which 75% of the total radiation falls the temperature does not vary 65 by as much as 15° C. and in which over the whole of a surface on which 90% of the total radiation falls the temperature does not vary more than 50° C.

According to the invention in a lamp of the 70 type specified wherein the discharge is adapted to consume more than 250 watts and in which the discharge column is more than 100 mm. long, the luminescent material is carried on the interior surface of a sealed outer jacket surrounding the discharge envelope, the space between the

said jacket and envelope being occupied by a gas at a pressure greatly below atmospheric, and the said jacket is so shaped that, when exposed in free air in full operation, the temperature over a part of the surface of the said jacket on which 5 75% of the radiation falls does not vary by as much as 15° C., the mean temperature of this part of the surface lying between 140° C. and 300° C., and the temperature over a part of the surface on which 90% of the radiation falls does 10 not vary by more than 50° C.

One embodiment of the invention will now be described with reference to Fig. 3 of the accompanying drawings, which show a broken axial section through a lamp and a curve indicating 15 the distribution of temperature over it.

In the drawings 11 is the glass inner envelope of a 400 watt high-pressure mercury-vapor discharge lamp of a known commercial type. It hangs vertically, as usual, from the screw cap 12. 20 From this cap hangs also the sealed pear-shaped outer jacket 13, which is of glass about 1 mm. thick, coated internally with zinc-cadmium sulfide activated by copper. The parts are drawn to scale, the dimensions marked A, B, C being 25 respectively 340, 165, 52 mm. The space between the jacket 11 and the vessel 13 is filled with dry oxygen at 10 mm. pressure. The jacket 13 is surrounded by free air, so that the temperature is 30 substantially constant along any circle on its surface in a horizontal plane.

The chart alongside the figure shows in a manner obvious to those skilled in the art how this temperature varies over the surface. The temperature is given only for the region between the 35 horizontal planes X and Y. The proportion of the radiation falling on the jacket outside these planes is considerably less than 10%; the planes could be moved towards each other so that each passed through the adjacent points at a temperature of 130° C. and the proportion of the radiation falling outside them would still be less than 10%. Accordingly in this embodiment the temperature over a part of the surface on which 40 90% of the radiation falls does not vary by more than 40%. The central part of the surface over which the temperature does not vary by 15° C. receives at least 75% of the radiation and the mean temperature of this part is between 150 and 45 160° C.

In order to ascertain how far these measurements could be repeated, two other lamps intended to be similar were made and the temperatures over their surfaces measured. The results are shown in Figure 2 of the accompanying drawings 55 in a manner similar to that adopted in Fig. 3. The temperature measurements extend from the bottom of the jacket ($X=0$) to a point on the neck of the jacket 250 mm. distant. The points indicated by crosses refer to tests on one of these 60 lamps, those indicated by circles refer to the other; the dotted line is the temperature curve of Fig. 3 reproduced for comparison.

It is to be observed that there are minor discrepancies which are, in part at least, due to experimental errors. If the average error for a large number of lamps was drawn, apparent irregularities would be smoothed out and the said limit of 15° C. could certainly be reduced, probably to 10° C.

It is not necessary that the whole of the interior of the jacket should be coated with the luminescent material; but no advantage is known from leaving any considerable part of it uncovered, except possibly if it is desired to obtain lights of

different colour in different directions. The luminescent material on the jacket will act to some extent as a diffusing surface, promoting the mixture of primary and secondary light. But the 5 surface of the globe, either that which bears the luminescent material or that which does not, or the glass of which it is composed, may be rendered diffusing in known manner so as to promote mixture further. Again the lamp may be associated 10 with diffusing surfaces outside the globe, so long as they form part of a fitting in which the lamp is placed and not an integral part of it, so as to increase its bulk. But it is not always necessary to produce a perfect mixture of the primary 15 and secondary light; that is to say, the ratio of the quantity of secondary to the quantity of primary light received by an observer at a distance may vary with the position of the observer. Thus in street lighting it is generally permissible 20 that the light emitted at large angles to the vertical should be less perfectly corrected for colour than light emitted near the vertical; such a dif-

ference is likely to be secured by the use of a jacket according to the invention, without subsidiary diffusing means.

We claim:

An electric gaseous discharge lamp comprising an elongated tubular vapor arc device of the type adapted to operate with a constricted arc discharge, a jacket about said device, said jacket having a modified prolate spheroidal shape wherein in the lower end is more drawn out than the upper, the distance of every point on said jacket from said device, with the exception of those portions lying beyond the ends of said device, being such that when said lamp is operated with the axis of said device vertical the temperature of 10 said points does not vary substantially from the mean temperature thereof, and a coating of a fluorescent material on the inner surface of said jacket. 13
